DESIGN FOR A LUMINAIRE

Leroy C. Doane, Meriden, Conn., assignor to The
Sight Light Corporation, Essex, Conn., a corpo-
ration of Connecticut

Application December 21, 1938, Serial No. 81,916

Term of patent 14 years

To all whom it may concern:

Be it known that I, Leroy C. Doane, a citizen of the United States of America and a resident of Meriden, in the county of New Haven and State of Connecticut, have invented a new, original, and ornamental Design for Luminaires, of which the following is a specification, reference being had to the accompanying drawing, forming a part thereof.

Figure 1 is a top plan view of the luminaire showing my new design;

Figure 2 is a side elevational view; and

Figure 3 is a fragmentary vertical sectional view.

I claim:

The ornamental design for a luminaire, as shown.

LEROY C. DOANE.
